UNITED STATES PATENT OFFICE

144,705

DESIGN FOR A HELICOPTER

Antoine Gazda, Providence, R. I.

Application March 12, 1945, Serial No. 118,417

Term of patent 7 years

(Cl. D71—1)

To all whom it may concern:

Be it known that I, Antoine Gazda, a citizen of no country, residing in Providence, Providence County, and State of Rhode Island, have invented a new, original, and ornamental Design for a Helicopter, of which the following is a specification, reference being had to the accompanying drawing, forming a part thereof.

Fig. 1 is a top plan view of a helicopter showing my new design, a portion of a propeller blade being broken away for convenience of illustration,

Fig. 2 is a front elevational view of the helicopter shown in Fig. 1, and

Fig. 3 is a side elevational view of the helicopter shown in Fig. 1.

The opposite side of the helicopter is of substantially the same appearance as that shown in Fig. 3.

I claim:

The ornamental design for a helicopter, as shown and described.

ANTOINE GAZDA.
